UNITED STATES PATENT OFFICE.

BANKS L. MILLER, OF SAN JUAN, TEXAS.

ORCHARD HEATER.

Application filed April 30, 1923. Serial No. 635,634.

To all whom it may concern:

Be it known that I, BANKS L. MILLER, a citizen of the United States, residing at San Juan, in the county of Hidalgo and State of Texas, have invented certain new and useful Improvements in Orchard Heaters, of which the following is a specification, reference being had to the accompanying drawings.

This invention relates to orchard heaters, 10 as they are called, of the type illustrated in my Patent #1,458,536, granted on June 12, 1923, heaters of this character including a base forming a grate for the support of a column of coke, charcoal or the like, and a 15 casing extending upward from and removable from the base within which the coke is burned.

While I do not wish to be limited to this use, yet heaters of this character are particularly designed for use in orchards for the purpose of preventing frost and are particularly designed for burning what is known as petroleum coke, such a heater being provided with a body and a grate, the grate being designed to hold a certain amount of petroleum or like oil and support the bed of coke thereon so that the bed of coke may be ignited by the burning oil.

One of the objects of the present invention 30 is to provide a grate which constitutes a base for the heater casing, this grate being so constructed that a column of air will be admitted at the center of the grate and carried upward through the body of coke in the casing so that the center or core of the coke will be most highly heated and that combustion will be reduced outward from the casing, thus causing the casing to last a much longer time than it otherwise would.

40 A further object is to provide a construction of this character wherein the base is formed to provide a central grate, there being an annular trough extending around the grate and which is designed to be supplied with fuel oil, this trough having an outwardly projecting lip extending beyond the periphery of the casing and of the grate so as to permit oil to be poured into the trough without removing the sheet iron casing.

50 Another object is to so construct the casing and grate that a certain amount of air may be uniformly distributed around the exterior of the coke or between the exterior of the coke and the wall of the casing.

55 Still another object is to provide a burner of this character so constructed as to elimi-

nate excessive heat adjacent the sheet iron drum or casing and which is so formed as to secure an even distribution of the air at the extreme bottom of the column of coke to 60 thus give a steady and even distribution of heat adjacent the ground, thus permitting the body which holds the coke and throws out the heat to be constructed in a very simple and inexpensive manner, and further 65 permitting the body to be so constructed that it may be reversed when one end has been more or less burned out.

A further object is to provide a rain cover adapted to be placed on the top of the casing 70 or drum and which when so placed acts to extinguish the fire within the drum.

Other objects will appear in the course of the following description.

My invention is illustrated in the accompanying drawings, wherein:

Figure 1 is a perspective view of an orchard heater constructed in accordance with my invention;

Figure 2 is a horizontal sectional view 80 through the body of the heater, the base being shown in plan;

Figure 3 is a fragmentary vertical sectional view on the line 3-3 of Figure 2.

Referring to the drawings, it will be seen 85 that my improved heater consists of three parts, namely a base 10, a sheet iron cylindrical body or drum 11, and a cover 12. The sheet iron body is imperforate and may have any desired diameter. The cover 12 90 has a central handle and a depending flange 13 which fits over the body 11 and this cover is imperforate. The base 10 is in the form of a grate and is of cast iron. It has a central, upwardly extending, circular wall 14 95 formed to provide at its upper end the transversely extending integral grate bars 15 which are, of course, spaced from each other.

The base is formed with an exterior integral trough 16 designed to contain oil. 100 The outer wall 17 of the trough is the same height as the inner wall 14. An air space 18 is left below the grate and the bottom of the trough 16 forms in effect an annular base adapted to rest upon the ground. At 105 one point the trough is formed with an inwardly extending air duct 19 which is in the form of an archway extending diametrically inward to the central air chamber 18, the wall forming this arched duct being 110 designated 20. Above this arched wall 20 the outer wall 17 of the trough is opened at

21 and a lip 22 is formed in the outer wall 17 which extends outward and forms a receiving cup, or in other words an extension of the wall 20. The side walls 23 of this cup 5 extend inward half way along the arched wall 20. Thus it will be seen that when the cylindrical body is disposed upon the base and filled with coke that the fuel oil may be poured into the cup or lip 22 and will flow 10 inward and be discharged on top of the wall 22 and then be discharged laterally into the annular trough so that from time to time this annular trough may be filled with oil. A wick as, for instance, an asbestos wick 24 15 may be disposed at one end in the cup 22 and at its other end extend beyond the walls 23 and into the annular trough, this wick being provided for the purpose of igniting the oil in the annular trough.

20 It will be noted that the outside wall 17 of the trough is sinuous in form so as to provide alternate re-entrant and re-extrant portions. The wall is re-entrant at the points 25 and it will be seen that when the 25 cylindrical body 11 is in place on this wall and resting upon the projections 26 that the re-entrant portions 25 will extend inward of this cylindrical body and that thus air may pass up in the space between the body and the wall 17 at uniform distances around the 30 entire mass of coke contained within the body.

In the operation of this device, the circular trough in the cast iron grate is filled 35 with any type of fuel oil or combustible oil and the sheet iron body is placed over the grate. Petroleum coke is then dropped in the drum in the crude lump form and the rain cap is placed on the drum to prevent 40 water from getting into the starting oil. The heater may then be lighted by means of the wick 24 or by pouring burning gasoline from a torch into this filling lip, which ignites the oil in the annular trough and the 45 oil lights the coke. No further adjustment is required in its operation. The heater is so constructed that the fire may be put out by placing on the rain cover or lifting the sheet iron body from off the base and letting 50 the coke slide out on the ground.

It will be seen that with this construction 55 fresh air is taken directly from the outside atmosphere and discharged within the center of the burning coke, giving the most intense heat up through the center mass of coke, thus eliminating excessive heat adjacent the sheet iron drum. This causes the drum to last several times as long as the ordinary drum. The corrugated outer wall 60 of the base admits and distributes the air evenly at the extreme lower end of the column of coke, which thus gives a steady and even distribution of the heat adjacent the ground. Such a construction as this permits the body to be formed simply as a 65

cylinder of sheet iron. Inasmuch as this hollow body is the same size at either end, it is obvious that it may be reversed so that when one end has been burned out the body may be inverted upon the base, giving the 70 heater double life. The drum may be recharged with coke while burning and as fast as the coke burns the unburned coke moves downward in the drum. The fire may be put out by placing on the rain cover 13 or 75 the whole device may be disassembled by removing the body from the grate, which will permit the coke to slide out on the ground. The fire then goes out by reason of not having proper draft. 80

I claim:—

1. A heater of the character described comprising a base and a cylindrical body detachably resting upon the base, the base being formed to provide a central grate, and a depressed annular trough surrounding the grate, the body being adapted to rest upon the outer wall of the trough, the trough being formed at one point to provide an inwardly extending air duct opening below the grate and the outer wall of the trough being formed with an outwardly projecting lip communicating with the interior of the trough. 85

2. In a burner of the character described, a base, a hollow body adapted to rest at its lower end upon the base and be detachably supported thereby, said base comprising a central grate and an outer integral annular trough whose walls extend below the grate, 100 the bottom of the trough at one point being formed with an arched passage extending radially inward from the exterior wall of the trough to a point below the grate, the top wall of said arched duct being continued 105 outward beyond the outer wall of the trough and having side flanges to form a receiving lip. 90

3. A heater of the character described comprising a base and a cylindrical body 110 adapted to rest upon the base, the base being formed to provide a central grate, and a depressed annular trough surrounding the grate, the trough at one point being formed to provide an air duct extending radially 115 inward from the exterior wall of the trough to the interior wall thereof. 95

4. In a heater of the character described a base and a cylindrical sheet iron body adapted to be disposed upon the base and 120 be supported thereby, the outer wall of the base being sinuous to thereby provide re-entrant portions extending inward beyond the cylindrical body to permit the entrance of air. 125

5. A heater of the character described comprising a base and a cylindrical body mounted thereon, the base being formed to provide a central grate and an annular oil trough extending around the grate, the 130

outer wall of the oil trough being sinuous to thereby provide re-entrant portions extending inward beyond the cylindrical wall to permit the entrance of air, the trough 5 being formed with an air duct extending radially intersecting the trough and opening into the central portion of the base below the grate.

6. A heater of the character described 10 comprising a base formed to provide a grate

and an oil channel, the grate being disposed above the bottom of the base, and means being provided for permitting air to enter beneath the grate, a cylindrical sheet iron body adapted to rest upon the base and extend upward therefrom, and a cover removable from the body.

In testimony whereof I hereunto affix my signature.

BANKS L. MILLER.
